(57) **CLAIM**

The ornamental design for a docking station, as shown and described.

DESCRIPTION

FIG. 1 is a front-left-top perspective view of a docking station showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines are for the purpose of illustrating portions of the docking station and form no part of the claimed design.

The dash dot lines illustrate boundaries of the claimed design, wherein the dash dot lines and the portion between the dash dot lines forms no part of the claimed design.

1 Claim, 5 Drawing Sheets(56)
